UNITED STATES PATENT OFFICE.

JOHN B. HIGGINS, OF BOSTON, MASSACHUSETTS.

CHECK-HOOK.

SPECIFICATION forming part of Letters Patent No. 367,810, dated August 9, 1887.

Application filed October 18, 1886. Serial No. 216,516. (No model.)

To all whom it may concern:

Be it known that I, JOHN B. HIGGINS, a citizen of the United States, and a resident of Boston, in the county of Suffolk and State of Massachusetts, have invented new and useful Improvements in Terrets and Checkrein-Holders, of which the following, taken in connection with the accompanying drawings, is a specification.

10 This invention relates to improvements in terrets and checkrein-holders, and it is carried out as follows, reference being had to the accompanying drawings, wherein—

Figure 1 represents a front elevation of my 15 invention, and Fig. 2 represents a side elevation of it. Fig. 3 represents a vertical section on the line A B, (shown in Fig. 2;) and Fig. 4 represents a vertical section on the line C D, (shown in Fig. 1.)

20 Similar letters refer to similar parts wherever they occur on the different parts of the drawings.

a is a ring, made of wood, bone, metal, or other suitable material, such ring having an 25 annular groove on its outer periphery, in which fits the split ring b, the latter having in its lower portion a split screw-threaded shank, b', as shown in Figs. 3 and 4. The split screw b' is screwed into the screw-threaded socket c, 30 made in one piece, with the flange c' and lower screw-threaded shank, c", which latter is adapted to be secured to the saddle or pad of the harness. Between the lower portion of the split ring b and the flange c' is located the 35 perforated base d', that surrounds the socket-piece c, and is provided with an upwardly-projecting rod or post, d, located back of the ring a and projecting above the top of the latter, as shown in the drawings, such rod or post 40 serving to receive the loop of the checkrein after it has been passed through the ring a, and when the loop of the checkrein has been so secured to the post or rod d it is impossible to get detached from it, except at the will of 45 the person in charge of the horse or animal.

The ring a can be readily turned around its axis within the split ring b, to adjust it therein

in case one portion should become worn by the chafing of the rein. This is a great advantage, as the ring a can be easily turned around when 50 one portion of it is worn more than the other, and it will thus retain its usefulness much longer than stationary rings.

In using the device as a terret I dispense 55 with the rear projecting rod or post d and adjust the ring a within the split ring b, according as it becomes worn by the chafing of the rein.

When the device is to be used as a checkrein-holder, I may prefer to make the ring a 60 stationary in relation to the other parts.

This invention is very simple in its construction, and offers perfect safety in preventing the checkrein from getting accidentally detached by the motion of the animal. 65

What I wish to secure by Letters Patent and claim is—

1. In a checkrein-holder, the ring a, in combination with the substantially vertical rod or post d, arranged on the rear and entirely outside of the said ring a, as and for the purpose set forth. 70

2. In a checkrein-holder, the split ring b, having the split screw-threaded shank b', and the ring a, made adjustable within said split ring, in combination with the rod or post d, arranged at the rear of said ring a, as and for the purpose set forth. 75

3. In a rein-holder, the ring a, and the split ring b, with its split screw-threaded shank b', 80 arranged as described, in combination with the socket c, having flange c' and screw-threaded projection c", and the post or rod d, with its perforated base d', substantially as and for the purpose set forth. 85

In testimony whereof I have signed my name to this specification, in the presence of two subscribing witnesses, on this 15th day of October, A. D. 1886.

JOHN B. HIGGINS.

Witnesses:

ALBAN ANDRÉN,
HENRY CHADBOURN.
